UNITED STATES PATENT OFFICE.

MONROE SUNSHINE, OF NEW YORK, N. Y.

SAD-IRON.

1,209,227.

Specification of Letters Patent. Patented Dec. 19, 1916.

Application filed February 15, 1913. Serial No. 748,765.

To all whom it may concern:

Be it known that I, MONROE SUNSHINE, a citizen of the United States of America, and resident of New York, in the county 5 and State of New York, have invented certain new and useful Improvements in Sad-Irons, of which the following is a specification.

This invention relates to sad irons and 10 more particularly to improvements in the iron shown in my prior Patent, No. 963,093, dated July 5, 1910.

The present invention relates to improvements 15 in the means for fastening the flame deflector to the body of the iron and to the means for pivoting the door, which closes the opening at the rear of the iron.

The features of novelty will be apparent 20 from the following description, taken in connection with the accompanying drawing, in which—

Figure 1 is a longitudinal section through 25 an iron embodying my invention. Fig. 2 is a rear elevation of the same; Fig. 3 is a detail of the door showing one form of pivoting means. Fig. 4 is a fragmentary longitudinal section of the body of the iron and showing a form of recess for receiving the door pivot.

Referring to the drawings, 10 indicates 30 the body of the iron, which is substantially as shown in my aforesaid prior patent, and which is provided with a burner 11, the latter being supplied by a suitable pipe 12. Arranged within the body 10 is the heat 35 deflecting plate 13 which is held in position and pressed against the bottom wall of the body by a suitable bolt 14, this bolt having threaded engagement with the top wall 15 of the body. At the rear of the body is an opening 16 which is normally closed by a door 17. In accordance with one form of 40 my present invention, as shown in Fig. 2, I form integrally with the door 17 the pivots 18 and 19, the pivot 18 being arranged 45 in a circular recess 20 in one of the side walls of the body, and the pivot 19 being arranged in a recess 21 in the opposite side wall, the latter recess extending upwardly to permit the door to be inserted by lowering the pivot 19 in the recess 21 when the door is in open position. From Fig. 2 it will be seen that the recess 21 extends 50 nearly to the upper edge of the opening 16 and in Fig. 4 I have illustrated another 55 form of the invention in which the recess

21^a instead of extending to the upper edge of the opening 16 has a lateral extension 21^b which permits the pivot 19 to be inserted from the rear. The recesses 21, and 21^a with its lateral extension 21^b, form elongated recesses each having a seat at its lower end for a coöperating hinge pivot.

In Fig. 3 I have shown another form of the invention in which the door 17^a has its 65 pivots 18^a and 19^a arranged loosely in recesses 22 and pressed outwardly by suitable springs 23. This arrangement permits the use of recesses for the pivots, in the side walls, which are similar to the recess 20 70 shown in Fig. 2.

For the purpose of holding the door in the closed position, I have provided a latching member 24 which swings on a pivot 25 secured to the body of the iron. The latching 75 member engages a projection 26, on the door, having an inclined outer surface whereby the latching member is adapted to clamp the door in closed position. In order to hold the latching member out of the path of 80 movement of the door when the latter is opened I have provided a stop 27 on the top wall of the body which is adapted to engage the latching member and hold the same. For convenience in opening and closing the 85 door, I have provided a handle or a thumb piece 28 thereon.

In the form of invention shown in Figs. 1 and 2 I have provided the upwardly projecting lugs 29 on the top wall of the body 90 for the purpose of supporting the handle plate 30 out of contact with the top wall, in order to practically insulate the handle plate from the body of the iron. The handle plate 30 is provided with an opening for the bolt 95 14, the latter projecting above the handle plate and being provided with a nut 31 which is adapted to clamp the plate against the lugs 29. The lugs 29 preferably engage recesses 32 in the under side of the handle 100 plate for the purpose of preventing the latter from turning about the bolt 14.

It will be seen from Fig. 1 that the construction just described is very simple, and the deflector 13 and the handle plate are 105 securely held in position by the single bolt 14.

It is to be noted that the removable door 17 or 17^a is inserted in position in the body by first putting pivot 18 or 18^a in its recess 20. As clearly shown in Fig. 2 the recess is 110 larger than the pivot so that the pivot fits loosely therein. Consequently the door can

be moved to a certain extent in any direction about pivot 18 or 18^a in the recess. That is, the loose fit permits a universal pivot action. After pivot 18 or 18^a has been inserted 5 in its recess, the door is then manipulated or swung about the said pivot so as to insert the other pivot 19 or 19^a in its recess. Of course the door shown in Fig. 3 might be inserted by simultaneously pressing both pivot 10 pins into the recesses 22, but it is much easier to first insert pin 18^a in its recess in the body, and then the pivot 19. Furthermore it should be observed that this manipulation 15 of the door does not require that the handle plate be first removed.

Having thus described my invention, what I claim is:

1. In a sad iron, the combination of a hollow body provided with an opening in one of 20 its side walls, said body formed with a circular recess in one edge of said opening and an alined recess formed in the opposite edge, and a door for said opening having oppositely 25 projecting hinge pivots, one of which

is adapted to fit loosely in said circular recess and the other of which is adapted to be inserted in the said alined recess by swinging the door about the first pivot after it has been placed in its recess. 25

2. In a sad iron, the combination of a hollow body provided with an opening in one of its side walls, said body formed with a circular recess and an oppositely arranged elongated recess forming a seat at its lower end alined with the circular recess, and a 30 door for said opening having oppositely projecting hinge pivots, one of which is adapted to fit loosely in said circular recess and the other of which is adapted to be placed in the said seat by sliding the 35 same in the elongated recess after the first pivot has been inserted in its circular recess.

In testimony whereof I affix my signature in presence of two witnesses.

MONROE SUNSHINE.
